UNITED STATES PATENT OFFICE.

MARK E. FERNALD, OF SAUGUS, MASSACHUSETTS, ASSIGNOR TO C. C. BLAKE, INCORPORATED, OF BOSTON, MASSACHUSETTS, A CORPORATION OF NEW YORK.

LACED UPPER AND METHOD OF LACING UPERS.

1,274,700.

Specification of Letters Patent.

Patented Aug. 6, 1918.

Application filed August 21, 1915, Serial No. 46,734. Renewed October 6, 1917. Serial No. 195,177.

To all whom it may concern:

Be it known that I, MARK E. FERNALD, a citizen of the United States, residing at Saugus, in the county of Essex and State of Massachusetts, have invented a new and useful Improvement in Laced Uppers and Methods of Lacing Uppers, of which the following is a specification.

The present invention relates to devices for lacing together the fly of a shoe upper preparatory to placing it on the last for the lasting and other operations in order that the edges of the fly or lacing slit shall be held at the proper distance apart and the upper properly fitted to the last during the lasting operation.

The object of the present invention is to provide a simplified and improved method of lacing uppers.

To the accomplishment of this object and the production of a novel lacing device the features of the present invention consist in certain methods, devices, combinations and arrangements of parts fully set forth hereinafter, the advantages of which will be readily understood by those skilled in the art.

The various features of the present invention will be readily understood from an inspection of the accompanying drawings, in which,

Figure 1 is a plan showing the sheet of fabric, the studs formed therein, and the cord inserted through the studs;

Fig. 2 is a longitudinal sectional elevation of a laced shoe upper;

Fig. 3 is a lateral sectional elevation of a laced shoe upper;

Fig. 4 is a perspective of a laced shoe upper, and

Fig. 5 is a perspective showing a modification.

In the illustrated embodiment of the invention the fly of the upper comprises the quarters 2 separated by the usual lacing slit 1 and having the usual lacing holes 3 (Figs. 2 and 3) therein which may be eyelets, blind eyelets or punch-holes in the upper.

In order to hold the edges of the fly or lacing slit at the required distance apart to insure the proper fitting of the upper to the last during the lasting operation, a sheet of fabric 4 is interposed between the tongue of the upper and the fly and a portion of the fabric adjacent each of the lacing holes

is stuffed therethrough forming a series of studs 5. This method of forming the studs 5 stretches the fabric, thus drawing the edges of the fly toward each other into position for the proper fitting of the upper to the last during the lasting operation (Fig. 3). After the studs 5 are passed through the lacing holes, a cord 6 is formed into two loops 7 and 8, and these loops are then inserted through the rows of studs 5 on both sides of the lacing slit (Fig. 4). To remove the cord the loose ends 9 and 10 of the cord (Fig. 4) are pulled, thus withdrawing the loops 7 and 8 from the studs.

In order to obviate the use of the cord, a sharpened stick, or rod 11, of metal, or fiber, may be inserted through the studs in the manner illustrated in Fig. 5.

It will be apparent to those skilled in this art and having the general object of the present invention in view, that changes may be made in the steps of the method and in the details of structure, the described and illustrated embodiment thereof being intended as an exploitation of its underlying essentials, the features whereof are definitely stated in their true scope in the claims hereto appended.

What is claimed as new, is:—

1. That improvement in the art of lacing uppers which consists in assembling a sheet of fabric with the fly, forming studs in the fabric and passing them through the lacing holes, and inserting a fastening through each of the studs on the side of the fly opposite the sheet of fabric, substantially as described.

2. That improvement in the art of lacing uppers which consists in assembling a sheet of fabric with the fly, drawing the edges of the fly together, forming studs in the fabric and passing them through the lacing holes, and then inserting a fastening through each of the studs on the side of the fly opposite the sheet of fabric, substantially as described.

3. That improvement in the art of lacing uppers which consists in assembling a sheet of fabric with the fly, forming studs in the fabric and passing them through the lacing holes, and inserting a fastening through the rows of studs parallel to the edge of the fly, substantially as described.

4. That improvement in the art of lacing uppers which consists in assembling a sheet of fabric with the fly, forming studs in the

fabric and passing them through the lacing holes, forming two loops in a cord, and inserting the loops respectively through the rows of studs parallel to the edge of the fly, 5 substantially as described.

5. A laced upper comprising a fly provided with parallel rows of lacing holes, a sheet of fabric having studs formed therein and passed through the lacing holes, and a 10 fastening inserted through each of the studs on the side of the fly opposite to the sheet of fabric, substantially as described.

6. A laced upper comprising a fly provided with parallel rows of lacing holes, a 15 sheet of fabric stretched across the fly to draw the edges of the fly together and having studs formed therein passing through the lacing holes, and a fastening inserted through each of the studs on the side of the

fly opposite to the sheet of fabric, substantially as described. 20

7. A laced upper comprising a fly provided with parallel rows of lacing holes, a sheet of fabric having studs formed therein passing through the lacing holes, and a fastening inserted through each of the parallel rows of studs, substantially as described. 25

8. A laced upper comprising a fly provided with parallel rows of lacing holes, a sheet of fabric having studs formed therein 30 passing through the lacing holes, and a cord having two loops therein, one of the loops being passed through the row of studs along one edge of the fly and the other loop being passed through the row of studs along the 35 other edge of the fly, substantially as described.

MARK E. FERNALD.
